UNITED STATES PATENT OFFICE.

WILLIAM F. MOUGHLER, OF TOLEDO, OHIO, ASSIGNOR TO THE CAILLE BROTHERS COMPANY, OF DETROIT, MICHIGAN, A CORPORATION OF MICHIGAN.

GAME.

SPECIFICATION forming part of Letters Patent No. 741,528, dated October 13, 1903.

Application filed June 10, 1902. Serial No. 111,026. (No model.)

To all whom it may concern:

Be it known that I, WILLIAM F. MOUGHLER, a citizen of the United States, residing at Toledo, in the county of Lucas and State of Ohio, have invented certain new and useful Improvements in Games, of which the following is a specification, reference being had therein to the accompanying drawings.

The invention relates particularly to a machine for playing games of chance; and it consists primarily in a mechanism of the character referred to having a movable member preferably in the form of a wheel or disk, a plurality of projectable tablets and a corresponding series of tablet-selecting devices, the parts being so arranged and combined that upon the selection of one of the tablets and the spinning or rotating of the wheel the selected tablet may or may not be projected 20 or otherwise operated, according to the position the wheel assumes when brought to rest.

The invention further consists in the peculiar arrangement and combination of the various parts of the mechanism, as will be 25 hereinafter more fully set forth, and shown in the drawings, in which—

Figure 1 is a section through an embodiment of my invention. Fig. 2 is a section on line $x-x$, Fig. 1. Fig. 3 is a perspective view 30 of the machine, and Fig. 4 is a perspective view of a portion of the locking mechanism for the releasing device.

In the drawings thus briefly described the reference-letter A designates an inclosing 35 casing having formed therein an upper rectangular opening B, and in its lower portion and centrally of the casing a circular opening C and vertical slot D.

E is a framework within the casing, in 40 which is journaled in suitable bearings a wheel G, opposite the display-opening C. As shown, the wheel is preferably in the form of a disk provided with a plurality of concentrically-arranged series of apertures a, b, c, 45 and d, and having a notched or toothed periphery. Means are employed for rotating the wheel and also for positively stopping or arresting its movement shortly after it has been set in motion, so that the player will not 50 be obliged to wait until the wheel gradually comes to rest.

In construction the operating mechanism for spinning the wheel comprises a vertical lever H, carrying at its upper end a handle I, which projects through and is adapted to 55 be reciprocated within the slot D. At its lower end the lever carries a latch J, pivoted, as shown, and held in a vertical position relative thereto by means of a suitable spring K. The latch is provided with a finger L, 60 which when the lever H is actuated engages a stud or projection M upon the casing and is tripped thereby.

O is an operating-lever pivoted to the framework, carrying at one end a finger P, with 65 which the latch engages; Q is an arm upon this lever, which is connected to the casing by a suitable spring R.

S is a pawl upon the lever O, engaging a ratchet-wheel T, fixed to the disk or wheel, 70 as shown.

Upon the player or operator moving the handle I downwardly within the slot the latch described normally engages the projection or pin P. The lever O will be operated against 75 the tension of its spring R until the latch is tripped by the device described, when it will be released. Upon its upward movement, caused by the spring R, the pawl S engages the ratchet and the disk or wheel is rotated. 80 The operating-lever H is returned to its initial position by a suitable spring U.

The mechanism for arresting the movement of the wheel I have shown as automatic in 85 its operation and is of the following construction: V designates a lever pivoted to the framework, as shown, and carrying a lug or stop member W, which is shaped and adapted to engage with one of the notches or teeth in the periphery of the wheel G. At its pivoted 90 end the lever V carries an arm X, which bears constantly against a pin Y upon an extension Z of the lever O. A' is a dash-pot, the piston-stem B' of which carries stop-pins C' and D' and at its end a cross-bar E', which is connected to the base portion of the dash-pot by the springs F'. G' is a dog pivoted to the framework, one arm of which is adapted to project in the path of the pin D'. The other arm, H', is made heavier than its complementary arm, so that when the stop W is in engagement with the wheel G it will rest upon 95 100

a lug I' upon the lever V. J' is a spring inserted between the free end of the lever V and the casing and acting to force the lever, with the stop thereon, into engagement with 5 the wheel periphery.

During the downward movement of the lever O, forming part of the rotating mechanism for the wheel, the member or arm Z moves upwardly, engaging the pin C' upon the stem 10 of the dash-pot and forcing the stem outwardly against the tension of the springs F'. At the same time the pin Y engages the arm X of the lever V and causes the latter to move outwardly against the tension of its spring J', thereby withdrawing the stop or lug W from 15 the notch or tooth in the wheel periphery. Upon the outward movement of the lever V the dog G' drops by the action of gravity upon a suitable shoulder or lug therefor into a position adjacent to the lug I', thereby holding 20 the lever V out of engagement with the wheel to permit of the rotation of the latter. The lever O being returned to its initial position by its spring R, the stem of the dash-pot is 25 free to be returned by its springs F'. During its inward movement the pin D' thereon trips the dog G'. The lever V, carrying the stop W, is actuated by its spring J' and the rotation of the wheel positively stopped.

Within the upper portion of the casing are 30 mounted for vertical reciprocation in suitable guideways K' a series of tablets, such as L', the tablets, as shown, being mounted in parallel alignment. Each tablet is provided 35 with a link M', which pivotally connects the tablet with the free end of a bell-crank lever O', which is pivoted to the framework in the casing. The arm P' of the lever just described is connected to a latch Q', which is 40 pivoted to the framework by a spring R'. The latch is adapted to engage a pin S' upon the bell-crank lever O' and is held in engagement therewith by the spring R'. Spring-actuated mechanism is thus provided for projecting each tablet upwardly within the casing opposite the display-opening B, said mechanism being normally locked against the tension of its springs and the position of the tablets when locked being below the opening, as 45 shown.

A releasing mechanism is provided for the tablets, consisting of a series of releasing devices in the form of spring-actuated bars T', arranged in adjacency to the wheel for horizontal reciprocation in the framework previously described. These bars are mounted in vertical alignment with their inner ends opposite, one to each series of apertures in the disk. As shown in Fig. 1, each releasing device is provided with a cross-bar U', connected at its ends to the framework by suitable springs V'.

W' is a finger or arm carried by each of the cross-bars, adapted when the releasing-65 bar is projected through an opening in the wheel to engage and trip the latch of the tablet that it is adapted to operate.

Each of the releasing devices described is provided with an individual lock, consisting of a pin X' and a latch Y', arranged beneath 70 the bar and engaging the pin, as shown. The individual locks referred to are controlled by a series of tablet-selecting devices, such as Z', each consisting of a rod A², connected to the end of the latch Y' and extending upwardly through the casing, being provided with a knob B² upon its free end. The latches Y' are held normally in engagement with their respective pins through the medium of coil-springs C², interposed between the knobs 80 and the adjacent portions of the casing, as shown in Fig. 2.

In addition to the individual locks described a universal lock D² is employed for the entire series of releasing devices. This lock is 85 adapted to keep the reciprocating bar that has been released by the tablet-selecting device from out of contact with the wheel during its rotation.

The universal lock described comprises a 90 vertical bar E², connected at its ends to the framework by links F². When in its extended position, with its links in horizontal planes, it engages the series of cross-bars U' of the releasing devices and, as before stated, locks 95 said devices out of contact with the wheel. The operation of this universal bar is controlled by the automatic stopping mechanism for the wheel, it being connected to the lever V by a suitable connection G².

When the wheel or disk is at rest, the universal locking-bar E² is in a tilted position, as shown in Fig. 2, and the releasing devices are held out of contact with the wheel only by the individual locks.

In operating the machine the player selects the particular tablet he wishes projected by depressing the tablet-selecting device, the latter being held in its depressed position by means of a lug a' on the rod engaging the casing. The releasing device corresponding to the tablet that is desired to be operated is thereby unlocked and is projected either against or through the disk or wheel. The wheel is then rotated in the manner previously described and subsequently stopped. As the lever V of the stopping mechanism moves out of engagement with the wheel to permit the latter to rotate it operates the bar E² through the connection described, and the projected releasing device is withdrawn from 110 and held out of engagement with the disk or wheel while the latter rotates. As the wheel is brought to rest by the stopping mechanism the locking-bar E² is returned to its normally inactive position and the releasing device is projected toward the wheel.

If the position of the wheel when arrested is such that an aperture therein registers with the releasing device, the latter is projected through 120 the wheel and the arm W' upon said releasing device trips the latch controlling the tablet that has been selected. The tablet is then projected upwardly opposite the display-open-125

ing B. If, on the other hand, no aperture registers with the releasing device that is projected, it merely strikes against the wheel and the tablet is not operated. Upon the next 5 operation of the machine the tablet-releasing device previously operated is restored to its initial position and another, if desired, selected and operated. The wheel is then rotated and the releasing device previously operated together with the device that has been unlocked at the second operation of the machine are both actuated by the locking-bar E². The first releasing device is automatically locked against movement by its pin passing 15 over its latch against the tension of the spring upon the tablet-selecting device. The tablet that has been projected upon the prior operation of the machine is restored or reset by means of the universal bar A³. This bar, 20 as shown, extends in proximity to the series of bell-crank levers O' and is attached to the lever H, moving downwardly with said lever as the latter is depressed by the handle and engaging the bell-cranks O'. The levers O' 25 referred to are automatically locked in their depressed position in the manner and by the mechanism previously described.

If desired, an ascending series of numerals may be placed upon the tablet-selecting devices and corresponding numerals arranged 30 upon the tablets, the object of the game being to acquire first a predetermined number of points. Other matter, however, in addition to or in place of the numerals, may be 35 arranged upon the tablets—such, for instance, as information that when acquired would assist and be of value to the player in the continuance of the game.

What I claim as my invention is—

1. In a machine for playing games of chance, 40 the combination with a rotatable wheel or disk having a series of apertures, of means for rotating the wheel and mechanism for stopping its rotation, a series of normally locked spring-actuated tablets operatively associated with said wheel or disk, means adapted 45 to engage the apertures in the wheel or disk for releasing the tablets, the operation of said devices being determined by the position 50 of the wheel or disk when arrested, and means for selecting the tablet to be released.

2. In a machine for playing games of chance, 55 the combination with a rotatable disk having a series of apertures, of means for rotating the disk and mechanism for arresting its rotation, a series of projectable tablets operatively associated with said disk, and means adapted 60 to engage the apertures in the disk, for permitting the operation of one of the tablets when the disk is arrested.

3. In a machine for playing games of chance, 65 the combination with a rotatable disk having a series of apertures, of means for rotating the disk and mechanism for arresting its rotation, a series of projectable tablets operatively associated with said disk, means adapted 70 to engage the apertures in the disk for

permitting the operation of one of the tablets when the disk is arrested, and means for selecting the tablet to be projected. 70

4. In a machine for playing games of chance, 75 the combination with a rotatable disk having a series of apertures, of means for rotating the disk and mechanism for arresting its rotation, a series of projectable tablets operatively associated with said disk, and means adapted 80 to engage the apertures in the disk for permitting the operation of any one of said tablets.

5. In a machine for playing games of chance, 85 the combination with a rotatable wheel or disk having a series of apertures, of means for rotating said wheel and mechanism for stopping its rotation, a series of spring-actuated projectable tablets locked normally 90 against the tension of their springs, a series of spring-actuated releasing devices for the tablets adapted to engage one of the apertures, the operation of said devices being determined by the position of the wheel when 95 arrested, a locking mechanism for the series and an individual lock for each of the releasing devices, and a series of tablet-selecting devices controlling the individual locks.

6. In a machine for playing games of chance, 95 the combination with a rotatable wheel or disk having a series of apertures, of means for rotating said wheel and mechanism for stopping its rotation, a series of spring-actuated projectable tablets locked normally 100 against the tension of their springs, a series of spring-actuated releasing devices for the tablets adapted to engage the apertures, the operation of said devices being determined by the position of the wheel when arrested, 105 a locking mechanism for the series, and an individual lock for each of the releasing devices.

7. In a machine for playing games of chance, 110 the combination with a rotatable wheel or disk, of means for rotating said wheel and mechanism for stopping its rotation, a series of spring-actuated projectable tablets locked normally against the tension of their springs, 115 a series of spring-actuated releasing devices for the tablets, the operation of said devices being determined by the position of the wheel when arrested, a locking mechanism for the series and an individual lock for each of the releasing devices, and a series of tablet-selecting devices controlling the individual locks. 120

8. In a machine for playing games of chance, 125 the combination with a rotatable wheel or disk, of means for rotating said wheel and automatically-operating mechanism for stopping its rotation, a series of projectable spring-actuated tablets locked normally against the tension of their springs, a series of spring-actuated releasing devices for said tablets, the 130 operation thereof being determined by the position of the wheel when arrested, a universal lock for said series of releasing devices controlled by the automatically-operating stop

mechanism, an individual lock for each releasing device in the series, and a plurality of tablet-selecting devices controlling the operation of the individual locks.

- 5 9. In a machine for playing games of chance, the combination with a rotatable wheel or disk, of means for rotating said wheel and mechanism for stopping its rotation, a series of spring-actuated projectable tablets locked 10 normally against the tension of their springs, a series of spring-actuated releasing devices for the tablets, the operation of said devices being determined by the position of the wheel when arrested, a locking mechanism for the 15 series, and an individual lock for each of the releasing devices.

10. In a machine for playing games of chance, the combination with a rotatable wheel or disk having a series of apertures, of 20 means for rotating said wheel and automatically-operating mechanism for stopping its rotation, a series of projectable spring-actuated tablets locked normally against the tension of their springs, a series of spring-actuated 25 releasing devices for said tablets adapted to engage the apertures, the operation thereof being determined by the position of the wheel when arrested, a universal lock for said series of releasing devices controlled 30 by the automatically-operated stop mechanism, an individual lock for each releasing device in the series, and a plurality of tablet-selecting devices controlling the operation of the individual locks.

- 35 11. In a machine for playing games of chance, the combination with a rotatable wheel or disk, of means for rotating said wheel

and mechanism for stopping its rotation, a series of spring-actuated projectable tablets locked normally against the tension of their 40 springs, and a series of spring-actuated releasing devices for the tablets, the operation of said devices being determined by the position of the wheel when arrested.

12. In a machine for playing games of 45 chance, the combination with a rotatable wheel or disk, of means for rotating said wheel and mechanism for stopping its rotation, a series of spring-actuated projectable tablets locked normally against the tension of their 50 springs, a series of spring-actuated releasing devices for the tablets, the operation of said devices being determined by the position of the wheel when arrested, and means for selecting the tablet to be projected. 55

13. In a machine for playing games of chance, the combination with a rotatable wheel or disk having a series of apertures, of means for rotating the wheel and mechanism for stopping its rotation, a series of normally 60 locked spring-actuated tablets operatively associated with said wheel or disk, spring-actuated releasing devices adapted to engage the apertures in the wheel or disk, the operation of said devices being determined by 65 the position of the wheel or disk when arrested, and means for selecting the tablet to be released.

In testimony whereof I affix my signature in presence of two witnesses.

WILLIAM F. MOUGHLER.
